SEWING MACHINE

Aaron Gallens, New York, N. Y., assignor to
 Bunin, Gallens & Co., Inc., New York, N. Y.,
 a corporation of New York

Application February 6, 1936, Serial No. 62,559

3 Claims. (Cl. 112—168)

This invention relates to new and useful improvements in a sewing machine.

At the present time there are machines for sewing with a zig-zag stitch and other machines for sewing with a blanket stitch. The object of this invention is to provide a mechanism for attachment upon machines which sew with a zig-zag stitch whereby they may be converted very easily to sew with the blanket stitch when desired.

More specifically, the invention contemplates in combination with a machine capable of sewing a zig-zag stitch, a mechanism which may be placed into operation or removed from operation to control the sewing to change the type of stitch.

Another object of the invention is the construction of a device as described which is simple and durable and which may be manufactured 20 and sold at a reasonable cost.

For further comprehension of the invention, and of the objects and advantages thereof, reference will be had to the following description and accompanying drawings, and the appended 25 claims in which the various novel features of the invention are more particularly set forth.

In the accompanying drawings forming a material part of this disclosure:

Fig. 1 is a front elevational view of certain 30 parts of the mechanism of a sewing machine to which the addition, according to this invention, has been applied.

Fig. 2 is a bottom view of some of the mechanism shown in Fig. 1.

Fig. 3 is a sectional view taken on the line 3—3 of Fig. 1.

Fig. 4 is a sectional view taken on the line 4—4 of Fig. 3.

Fig. 5 is a sectional view taken on the line 40 5—5 of Fig. 2.

Fig. 6 is a sectional view taken on the line 6—6 of Fig. 2.

Fig. 7 is a sectional view on the line 7—7 of Fig. 2.

Fig. 8 is a sectional view on the line 8—8 of Fig. 2.

Fig. 9 is a schematic view showing the zig-zag stitch produced by the machine.

Fig. 10 is a schematic view showing the blanket 50 stitch produced by the machine.

The invention is intended, in combination with a sewing machine having a laterally extending drive shaft 10 provided with a crank 11 reciprocating a needle bar 12 journaled in a laterally vibratory frame 13. A reciprocating cloth feeder

14 is supported by a crank 15 in a pivotal shaft 16 capable of simultaneously raising and lowering the cloth feeder during the reciprocation thereof. A pitman 17 supporting the cloth feeder 14 as clearly shown in Fig. 8 is connected with a crank 18 mounted on a pivotal bar 19. This pivotal bar is equipped with another crank 20 moved by a pitman 21 connected with a cam 22 on the drive shaft 10.

The dot and dash lines 23 in Fig. 1 represent the conventional body of the sewing machine. This body is provided with bearings 24, also shown by dot and dash lines, which rotatively support the drive shaft 10. A pulley 25 is mounted on the extended end of the shaft 10 by which the sewing machine may be driven.

Within the body of the sewing machine there is a pulley 26 on the drive shaft 10 which connects with a flexible belt 27 extending over a pulley 28 on a shaft 29 within the pivotal shaft 20 16. This shaft 29 extends from the other end of the pivotal shaft and is provided with a gear 30 meshing with a gear 31 on a shaft 32 supporting the thread hook member 33 of the sewing machine. Up to this point the sewing machine is of conventional construction. Further details of the machine will not be given in this specification since they form no part of the invention and they are well-known in the art.

The invention comprises an auxiliary shaft 35 30 rotatively supported in bearings 36 and 37 upon the body 23 of the sewing machine. A gear reduction is housed between these shafts. This gear reduction comprises a pinion 38 upon the drive shaft 10 meshing with a gear 39 upon the auxiliary shaft 35. A cam 40 is mounted upon the auxiliary shaft 35 and is for the purpose of holding said vibratory frame 13 in one lateral position for a pre-determined number of cycles of the needle bar, and in another lateral position 40 for another pre-determined number of cycles of the needle bar.

More specifically, a rod 41 pivotally connects with the vibratory frame 13 and is supported by a pair of links 42 and 43. The link 43 is 45 pivotally supported at the end 43' upon the body 23 of the sewing machine. The links 42 and 43 are pivotally connected at their outer ends by a pin 44. The link 42 is pivotally connected at its inner end upon the rod 41. A spring 45 is connected between the extremity of the rod 41 and a pin 46 mounted upon the body 23 of the sewing machine. The spring 45 serves to hold the end of the rod 41 against the cam 40. The cam 40 has an enlarged portion 40a which is 55

capable of forcing the end of the connecting rod 41 upwards for a certain period of time. this upward motion is translated by the links 42 and 43 into a lateral motion which moves the 5 vibratory frame 13.

According to a preferred embodiment of the invention the cam portion 40a is of a size substantially one-third of the periphery of the cam so that the needle bar 12 will remain extended 10 towards the left as viewed in Fig. 1 for two cycles, and move to the right for one cycle. The ratio between the gears 38 and 39 is 1:3. Thus, for each three times the drive shaft 10 rotates the shaft 35 will rotate once.

15 Another cam 49 is mounted upon the auxiliary shaft 35 and is formed with a cam groove 49a having a portion thereof concentric with the auxiliary shaft 35 for two-thirds of the circumference and a portion extended radially from 20 the auxiliary shaft 35 for the remaining one-third of the circumference. A roller 50 works in this cam groove 49a and projects from the head 51a of a pitman 51. This pitman has an elongated slot 51b through which the auxiliary shaft 35 extends. The arrangement is such that the pitman may move vertically upwards and downwards. Furthermore, it will remain in one position for two-thirds of a revolution of the auxiliary shaft 35, and then in the remaining 25 one-third will move downwards and back upwards to its original position. This pitman 51 connects with a crank 52 releasably mounted upon the shaft 16. The crank 52 is composed of two sections engaged on opposite sides of the shaft 16 and fixedly held when desired by screws 35. When these screws are loosened the crank is free on the shaft 16.

Another cam 54 is mounted on the drive shaft 10 and operates a pitman 55 which is connected 40 with a crank 56 releasably mounted upon the shaft 16. This crank is provided with a screw 57 which may be tightened or loosened for connecting the crank with the shaft or disconnecting the crank. The crank 15 is connected with 45 a block 15a which slidably engages in a slot 17a in the pitman 17. The sliding of the block in the slot has no effect, but the turning of the crank 15 serves to raise or lower the cloth feeder 14 into operative or inoperative positions.

50 The operation of the device is as follows: Assume the crank 52 to be loose on the shaft 16 and the crank 56 to be tight on the shaft. When the device is in this condition the shaft 16 will have one cycle of oscillation for each rotation of the drive shaft 10. The cloth feeder 14 is therefore operating continuously to move the cloth forwards. For each rotation of the shaft 10 the bar 19 will oscillate once which will move the crank 18 and the pitman 17 so that the 55 cloth feeder 14 is reciprocated at the same time it is being moved upwards and downwards. These actions are harmonized as in a regular sewing machine so that the cloth feeder is in the raised position when moving forwards, and in the lowered position when moving rearwards. The machine is now sewing stitches as shown in Fig. 9. Thus a zig-zag stitch, though not a true zig-zag stitch, is formed because one of the points on one of the sides is flat. The stitch is 60 produced by the fact that the cloth feeder 14 is operating continuously and the needle makes two stitches on one side and the third stitch on the other side. The point 60 represents the first stitch on one side; the point 61 represents the second stitch on the same side; and the point 65 70 75

62 represents the third stitch on the other side. The cycle repeats, the next stitch being 60' on the first side, etc.

If it is desired to form blanket stitches the crank 56 is loosened on the shaft 16 and the 5 crank 52 is tightened on the shaft 16. The needle will continue to stitch two stitches on one side and one stitch on the other side, but the cloth feeder 14 will advance the cloth only once during each of its three stitches. The reason 10 for this is that the cam 49 holds the shaft 16 in a position in which the cloth feeder is lowered. Then, even though the bar 19 is oscillating which reciprocates the cloth feeder, the cloth feeder is inoperative as it is in a lowered position. During one-third of the revolution of the cam 15, the pitman 51 will be moved to pivot the pivotal shaft 16 so that the crank 15 lifts the cloth feeder 14 into operative position.

The stitch produced by this operation is shown 20 in Fig. 10 and may be traced as follows: The first stitch 60 is taken on one side; the cloth feeder moves to operate the cloth so that the second stitch occurs at the point 61. During the 25 third stitch the cloth feeder is inoperative so that the third stitch occurs at the point 62. The fourth stitch occurs at the point 60', and thus the operation continues.

In Fig. 10 the points 61 and 60' are really 30 superimposed, but for clarity in illustration they have been shown slightly spaced from each other.

While I have illustrated and described my invention with some degree of particularity, I realize that in practice various alterations therein may be made. I therefore reserve the right and privilege of changing the form of the details of construction or otherwise altering the arrangement of the correlated parts without departing 40 from the spirit of the scope of the appended claims.

Having thus described my invention, what I claim as new, and desire to secure by United 45 States Letters Patent is:—

1. In a sewing machine having a laterally extending drive shaft provided with a crank reciprocating a needle bar in a laterally vibratory frame, a longitudinally reciprocating cloth feeder supported by a crank on a pivotal shaft capable of simultaneously raising and lowering the cloth feeder during the reciprocation thereof, and a crank for reciprocating said cloth feeder mounted on a pivotal bar equipped with another crank moved by a pitman connected with a cam to said drive shaft, the combination of a cam on said drive shaft continually operating a pitman connected with a crank releasably mounted on said pivotal shaft, an auxiliary shaft, a gear reduction between said auxiliary shaft and said drive shaft, means including a cam on said auxiliary shaft for holding said vibratory frame in one lateral position for a pre-determined number of cycles of said needle bar and in another lateral position for another pre-determined number of cycles of said needle bar, another cam on said auxiliary shaft, a pitman periodically moved by said latter cam, and a crank connected with said pitman and releasably connected with said pivotal shaft whereby one of said releasably mounted cranks may be fixed on said pivotal shaft for causing the sewing machine to sew with one type of stitch, and then in succession said fixed crank may be released and said other crank fixed on said pivotal 50 shaft for causing the sewing machine to sew with another type of stitch.

2. The device as defined in claim 1, but in which the gear reduction has a ratio of 1:3 so that the drive shaft turns three times for each rotation of the auxiliary shaft, and in which the latter-mentioned cam on the auxiliary shaft moves the pitman once for each rotation thereof.

3. In a sewing machine, a stitch producing mechanism comprising, in combination, a laterally extending drive shaft provided with a crank reciprocating a needle bar in a laterally vibrating frame, a longitudinally reciprocatory cloth feeder supported by a crank on a pivotal shaft capable 15 of raising and lowering the cloth feeder simultaneously during the reciprocation thereof, a crank for reciprocating said cloth feeder mounted on a pivotal bar equipped with another crank moved by a pitman connected with a cam 20 to said drive shaft, an auxiliary shaft at right angles to said drive shaft, a casing encasing said

drive shaft and auxiliary shaft except for an extended end of the auxiliary shaft, a gear reduction between said auxiliary shaft and drive shaft, means including a cam on said auxiliary shaft for holding said vibratory frame in one lateral position for a pre-determined number of cycles of said needle bar, and in another lateral position for another pre-determined number of cycles of said needle bar, a cam body fixed upon the extended end of said auxiliary shaft and 10 slightly spaced from said casing and having its inner face formed with a cam groove, a pitman formed with an opening engaged upon said auxiliary shaft and being slidably mounted between said cam body and said casing, a pin on 15 said pitman engaging the cam groove of said cam body, said cam being adapted to periodically move the pitman, and a crank connected with said pitman and releasably connected with said pivotal shaft.
